Kamille Blechman, New York, N. Y.

Application October 17, 1938, Serial No. 235,429

3 Claims. (Cl. 2—192)

This invention relates generally to hats, but more specifically to a method of manufacturing turban hats.

The main object of the invention resides in the provision of a method of manufacturing turban hats whereby two turban hats may be manufactured from one hat body, resulting in the saving of labor and in the saving of material.

A further object of the invention resides in the provision of a method of manufacturing turban hats of any hat material made into hat bodies, the said resulting turban hats being capable of receiving the conventional trimming.

These objects and other incidental ends and advantages of the invention will hereinafter appear in the progress of the disclosure and as pointed out in the appended claims.

Accompanying this specification is a drawing illustrating the method of manufacturing turban hats from flexible hat bodies having crown and brim portions. In the drawing, corresponding reference characters designate corresponding parts throughout the several views thereof, the said views being as follows:

Figure 1 is a view in perspective of a conventional and flexible hat body.

Figure 2 is a view in diametrical section along the plane 2—2 of Figure 1.

Figure 3 is a view in perspective showing one-half of the hat body set forth in Figure 2 placed on die A with the concave portion resting on the top convex portion of the said die.

Figure 4 is a view in perspective of the hat shown in Figure 3, wherein the corners of the brim member are secured together, thereby resulting in the formation of a turban hat.

Figure 5 is a view in perspective of a turban hat showing the brim portion of Figure 4 intermediate the width thereof turned downwardly.

In accordance with the invention and the drawing illustrating the same, numeral 10 represents the crown of a flexible hat body while numeral 11 designates the brim thereof. The hat body may be of straw, felt or other flexible material conventionally used in the manufacture of ladies' hats. The said hat body containing the crown and brim portions is folded along the diametrical axis so that two identical halves are made from the one hat body, each half being provided with crown portion 10a and a brim portion 11a. Numeral 12 indicates the cut crown edge; 13 and 14 indicate the cut brim edges; 15 indicates the original semi-brim edge, while 16 and 17 indicate the corners of the cut brim edges 14 and 13 respectively.

Figure 3 illustrates the next step in the manufacture of two turban hats from one hat body after the said hat body is cut into two. Either one of the half hat bodies is set on a hot die A wherein concave crown portion 10a is made to set upon the top convex portion of the die A, thereby resulting in the formation of a turban hat body wherein the crown edge 12 is adapted to fit over the head of the wearer and the brim portion 11a is adapted to extend above the top 10 of the crown 10a.

The next step in the formation of the hat resides in the securing together of corners 16 and 17 of brim edges 14 and 13 respectively whereby the inner portions of edges 14 and 13 serve to form a continuation for edge 12 in the formation of a closed head engaging edge. As shown, corner 16 overlies corner 17 and is secured in this position by means of a line of stitching 18.

The turban hat is now ready to be trimmed. As shown in Figure 5, numeral 19 indicates gathering at the front of the crown portion, while numeral 20 indicates a turned down brim portion, the edges 15a and 15b indicating the lateral limits of brim edge 15 after the turning down operation. Of course, it is understood that other methods and means of trimming and decoration of the turban hat may be resorted to, such as the addition of pieces of hat material, the securing of pins, veils and feathers thereto and the like.

Thus has been described a method of manufacturing turban hats from hat bodies wherein two turban hats are made from each single hat body. Different sizes of turban hats may be made by using different sizes of hat bodies and dies. Hot dies may be employed for purposes of hat shaping by hand manipulation following the securing together of corners 16 and 17, if desired.

I wish it understood that minor changes and variations in the steps utilized in the method of manufacture of the hats may be resorted to without departing from the spirit of the invention and without departing from the scope of the appended claims.

I claim:

1. In a method of manufacturing of turban hats from hat bodies having crown and brim portions, the step of severing the hat body into half and then securing the ends of the brim corners of each half of the hat body together for the formation of two turban hats from a single hat body.

2. In a method of manufacturing of turban hats from hat bodies having crown and brim

portions, the step of severing the hat body into half, the step of securing the ends of the brim corners of each half of the hat body together for the formation of two turban hats, and the step of shaping the hat on a die.

5 3. In a method of manufacturing of turban hats from hat bodies having crown and brim

portions, the step of severing the hat body in half to form two turban hat bodies, the step of securing the ends of the brim corners of each of the turban hat bodies together on a die and the step of trimming the turban hat thus formed. 5
